REMOTE CONTROL ADJUSTING DEVICE

Mahlon W. Kenney, River Forest, and George
Oliver Smith, Chicago, Ill.

Application May 24, 1937, Serial No. 144,386

1 Claim. (Cl. 74—10)

This invention relates in general to remote control adjusting apparatus with more particular reference to an apparatus for adjusting radio receivers and the like from a remote point. The invention of this application is an improvement over that disclosed in the co-pending application of Mahlon W. Kenney, Serial No. 104,994, filed October 10, 1936.

It is an object of applicant's invention to provide a remote control system of the type shown in said co-pending application but of greater simplicity and compactness.

It is a further object of applicant's invention to provide in a remote control device for a radio receiver or the like embodying a station selector, vernier means to adjust the radio receiver or the like independently of the station selector.

It is a further object of applicant's invention to provide a remote control adjusting device for radio receivers or the like wherein the lost motion or back lash in the cable connecting such device to the operated device is eliminated, and wherein such remote control device embodies a selector mechanism for selecting any one of a certain number of broadcast stations according to their call letters, and additional means for tuning the receiver to other than said number of broadcast stations.

Referring to the drawing:

Fig. 1 is a side elevation showing applicant's invention with certain parts in section.

Fig. 2 is a vertical plan view partly in section taken along the line 2—2 of Fig. 1.

In Fig. 2 there is shown a station selector dial plate 1 having 15 apertures 2 arranged circumferentially, each aperture being of a size to accommodate the index finger of the person desiring to operate the dial. A central opening in the dial plate carries a glass plate 3, behind which is exposed a fixed translucent plate 4. The plate 4 carries the usual indicia representing the wave lengths or radio frequencies of radio broadcasting stations. The dial plate 1 is fastened to a pedestal 5 carried by the radial arms (not shown) of a wheel 6. The wheel 6 is provided with an annular rim 7 connected by said arms to a hub portion rotatably receiving an axle 8 supported in a boss 9 formed in a back plate 10. The back plate 10 may be fastened to any fixed support, for example, the dash of an automobile, and the fixed plate 4 may be secured to the fixed shaft 8 in any desired manner.

The wheel 6 is secured on the axle 8 against endwise movement by any suitable means (not shown). The annular rim 7 of the wheel 6 is

provided with concentrically arranged sets of apertures 11 and 12, the apertures 12 lying directly behind the openings 2 in the dial plate 1 and corresponding in number to the number of said openings. Pins 13, which slidably engage in the apertures 12, carry on their free ends collars or blocks 14 to which are fastened translucent cup-like members 15. The mouth of each cup-like member 15 is closed by a translucent plate which is secured to the cup by a metallic ring 16. The translucent covering plates are adapted to carry indications representing the call letters of the radio broadcasting stations most frequently selected by the particular operator, as exemplified in Fig. 2. The pins 13 are each urged by a spring 17 toward the dial plate 1 and in the normal outermost position are restrained against further outward movement by engagement of the flanges of the rim 16 with the inner edge of the rear countersunk portions of the openings 2. The collars 14 are centrally bored at right angles to the pins 13 and through the apertures thus provided there pass the legs 17 of right angle pins 18. The other legs of the pins 18 slidably engage in the apertures 11 in the rim 10 of the wheel 6. The apertures 11 may exceed in number the apertures 12 and may be arranged to provide for adjustment of each pin relative to its associated push button as shown in the co-pending application of Mahlon W. Kenney and Andrew A. Gedde, Serial No. 100,156, filed September 10, 1936. Upon inward operation of the push button carrying the call letters of the desired station, the pin 18 associated with that push button will be forced inwardly until one end projects beyond the inner edge of the rim 10 and the wheel 6. The pin 13 will likewise be forced inwardly against the action of the spring 17. The dial plate 1 is then rotated while maintaining the push button in its operated position and the rotation of the dial plate 1 causes rotation of the wheel 6 which is fixedly secured thereto. As described in the sole application of Kenney heretofore referred to, the pins 13 may operate contacts to de-energize the loud speaker of the radio during the tuning operation of the selector. The extending ends of pins 18 cooperate with a substantially fixed pin 19 to limit the rotative movement of the wheel 6 and dial plate 1 in the manner described in said sole application of Kenney.

The rim 1 of the wheel 6 is formed on its periphery with gear teeth 20 which mesh with anti-backlash gears 21 secured to a collar 22. The collar 22 is secured to a shaft 23 which extends parallel to the axle 8 of the selector and in juxta-

- position to said selector. The shaft 23 is journaled in a bearing 24 carried by a bracket 25 fixedly secured to the back plate 10 of the selector. The shaft 23 carries at its outer end a manually operable knob 26. The shaft 23 is connected by any suitable conventional coupling to one end of a flexible shaft 27, the other end of which is similarly coupled to a stub shaft 28 carried by the bracket 30, forming the front face of the housing for the usual tuning condensers 31. The shaft 32 of the tuning condensers carries at its outer end the anti-backlash gears 33 which mesh with a gear 35 carried by the stub shaft 28 between the brackets 29 and 30.
- 10 15 20 25 30 35
- As shown in the drawing, the gear formed by the teeth 20 of the wheel 6 and the gear 33 are larger in diameter than the gears 21 and 35 and therefore there is provided a step-up ratio between the selector mechanism and the flexible shaft and a step-down ratio between the flexible shaft and the tuning condensers for the purpose of minimizing the lost motion or backlash in the cable as described in the hereinbefore referred to sole application of Mahlon W. Kenney.

It will be seen from the above description that applicant has provided a simplified and compact driving connection between the selector and the flexible shaft for operating the tuning condenser and has provided an auxiliary manually operable vernier means for tuning the radio receiver independently of the station selector. Thus it is possible by operation of the auxiliary manually operable means accurately to tune the receiver to stations other than those indicated by the call letters of the station selector.

Changes may be made in the form, construction and arrangement of the parts without departing from the spirit of the invention or sacrificing any of its advantages, and the right is hereby reserved to make all such changes as fairly fall within the scope of the following claim.

5 The invention is hereby claimed as follows:

In a radio apparatus or the like, the combination of a tuning condenser, a rotatable dial plate having a plurality of finger-receiving openings, 10 a shaft, a gear rotatably mounted on said shaft and connected to said dial plate, a plurality of station selecting push buttons slidably mounted on said gear and arranged behind the openings in the dial plate, said push buttons carrying indicia 15 representative of certain broadcasting stations, means cooperating with a selected push button to stop the gear and dial plate in their adjusted position, a second rotatable shaft parallel to said first shaft, a second gear mounted on said second 20 shaft and engaging said first gear, a flexible shaft connected at one end to said rotatable shaft, gear means connecting the other end of said flexible shaft to said tuning condenser, said first and second gears having a step-up ratio and 25 said gear means having a step-down ratio for preventing phase displacements between the dial plate and tuning condenser, and a manually operable knob secured to said second rotatable 30 shaft for rotating said condenser to tune said receiver to any other desired broadcast station.

MAHLON W. KENNEY.

GEORGE OLIVER SMITH.
